ASH TRAY

William E. Powers, Dayton, Ohio

Application January 16, 1942, Serial No. 427,051

1 Claim. (Cl. 131—240)

This invention relates to an ash tray of the portable character which may be placed on any table, desk or other support with safety and will provide a maximum capacity for ashes and the accommodation of cigarette or cigar butts having a centrally arranged portion on which ignited cigarettes or cigars may be rested with a maximum amount of safety and which may be employed to easily and quickly extinguish a cigarette when desired.

Another object of this invention is the provision of means on the central portion of the device to support ignited cigarettes or cigars permitting free circulation of air thereabout to prevent cigarette or cigar sweating and consequently obviate the taste of the cigarette or cigar from being affected when left for a period of time thereon and in a burning state.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a top plan view illustrating an ash tray constructed in accordance with my invention.

Figure 2 is a vertical sectional view illustrating the device.

Figure 3 is a detail sectional view taken on the line 3—3 of Figure 1, showing means to prevent cigar or cigarette sweating when left rested on the device in a burning state.

Figure 4 is a view similar to Figure 3 illustrating a modified form of the invention.

Referring in detail to the drawing, the numeral 5 indicates the body of the device which is preferably of saucer shape having a flat bottom wall 6 and upstanding walls 7 integral therewith. An enlargement 8 is integral with the top face of the bottom wall 6 and terminates a distance above the vertical walls 7 defining within the body an annular recess 9 for the accommodation of a maximum amount of ashes, cigar or cigarette butts.

The portion 8 has formed therein a chamber or recess 10 and provided in the bottom wall 11 thereof with a series of tapered sockets 12 which may be employed for the extinguishing of burning cigarettes by the insertion of the burning end therein. The upper edge of the portion 8 has formed therein a series of recesses 13 to form rests for the accommodation of burning or ignited cigarettes or cigars.

In applying a cigar or cigarette in a burning state to the rest, the burning end is disposed either over the recess 9 or recess 10 and should

the cigarette or cigar burn to such an extent that it becomes unbalanced on the rest it will fall either into the recess 9 or 10 and consequently be prevented from falling on the floor, desk or other support on which the body 5 is placed.

The upper edge of the portion 8 of the body has arranged on opposite sides of the recesses 13 sockets for the accommodation of substantially U shaped supporting bars or members 13', the free ends of which are angularly disposed and positioned in the sockets, positioning the major portions of the bars within the recesses 13 and spaced from the major portions of the walls thereof to prevent contact of a burning cigar or cigarette therewith, allowing substantially free circulation of air about the supported portion of the cigar or cigarette which will eliminate to a minimum cigar or cigarette sweating.

By eliminating to a minimum cigar or cigarette sweating, the taste of the cigar or cigarette will be less affected when left burning in a rested position upon the device. The bars or members 13' may be easily removed for cleaning and also permit the walls of the recesses 13 to be easily cleaned.

Referring to my modified form of the invention, the recesses 13 may have formed in the walls thereof sockets 14 for the accommodation of pins 15 to take the place of the U shaped members 13'. It will be noted that the pins 15 are arranged in converging relation toward their supporting ends so that when a cigarette or cigar is placed thereon it will be supported away from the walls of the recess 13 and thereby allow a substantially free circulation of air thereabout to prevent sweating.

While I have shown and described the preferred embodiment of my invention, it will be understood that minor changes in construction, combination and arrangement of parts may be made without departing from the spirit and scope of the invention as claimed.

Having thus described the invention, what I claim is:

In an ash tray, a saucer-shaped body, an upstanding portion located centrally of and integral with the body and having a recess providing an annular upper edge thereto, said edge having recesses and sockets therein with the sockets located adjacent to and at opposite sides of the second-named recesses, and substantially U-shaped cigarette supporting members acting to prevent cigarette sweating arranged in pairs and traversing the last-named recesses and including angularly related end portions resting on the edge of the upstanding portion and extending into the sockets to prevent accidental displacement of said members.

WILLIAM E. POWERS.
